tality records were made after 24 hours. For aging, the treatments were held indoors at room temperature.

In the powder tests, the mixtures were applied to small balbriggan cloth patches and the insects were confined on the treated cloth. Examinations were made at various time intervals to determine their toxicity to the insects. The powders were handled and aged in the same manner as the cloth impregnants.

Tests against body lice were conducted to determine the immediate and residual effectiveness of certain of the organic phosphates when mixed with 1,2-methylenedioxy-4-[2-(octylsulfinyl)propyl]benzene as the synergist. Preliminary tests were run with the organic phosphates at several low concentrations in order to select dosages that would show synergistic action of the 1,2-methylenedioxy-4-[2-(octylsulfinyl)propyl]benzene.

Each organic phosphate was tested at a range of three concentrations, alone and combined with the synergist. A ratio of 1 part of the organic phosphate toxicant to 10 parts of the synergist was used in these tests, although synergism was evident with other ratios. In a second series of tests the phosphates were tested for residual effect at a concentration of 0.005 percent alone and combined with 0.05 percent of the synergist. In these tests 1-hour knock-down records were taken in the initial exposures and 24-hour exposure tests were conducted twice weekly for 3 weeks.

In the first series of tests, the results of which are shown in Table 1, the synergist caused remarkable increases in the effectiveness of both phosphates. An 0.005 percent concentration of the toxicant alone caused only 20 and 10 percent knock-down and 0 and 10 percent kill in 24 hours, while with the synergist the knock-down and kill were 100 and 90, and 100 and 70 percent, respectively. Half this concentration of the toxicant was completely ineffective in both cases, but when combined with the synergist, the knock-down and kill were 100 and 85, and 100 and 60 percent. The synergist namely, 1,2-methylenedioxy-4-[2-(octylsulfinyl)propyl]benzene(sulfoxide), alone at 0.05 percent was completely ineffective. The other synergist, namely, the alpha-isopropylpiperonyl ester of chrysanthemum monocarboxylic acid, alone at .05% was similarly substantially complete ineffective.

Table 1.—Results of beaker tests with umbelliferone phosphate compounds at low concentrations alone and combined with a synergist, 1,2-methylenedioxy-4-[2-(octylsulfinyl)propyl]benzene. (Ratio of toxicant to synergist 1:10; 20 adult lice (10 of each sex) exposed for 24 hours.)

Item No.	Toxicant	Percent concentration		Percent knock-down ¹ and mortality after 24 hours	
		Toxicant	Synergist	Knock-down	Mortality
15	O,O-diethyl O-4-methylumbelliferone thiophosphate	{ 0.005 .0025 .001 .005 .0025 .001 .005	{ 0.05 .025 .01 ----- 0 0 .05 .025 .01 .005 .025 .001	{ 100 100 5 20 0 0 100 100 15 10 15 0	{ 90 85 0 0 0 0 70 60 15 10 5 0
20	O-(3-chloro-4-methylumbelliferone) O,O-diethyl thiophosphate	{ 0.001 .005 .0025 .001	{ .01 .025 .01 ----- 0 0 10 15 0	{ 15 10 15 0	{ 15 10 5 0
	Check—untreated	-----	-----	0	0

¹ Knock-down also includes those listed as dead.

Seventeen other materials acted as synergists for the O,O-diethyl O-4-methylumbelliferone thiophosphate, O-(3-chloro-4-methylumbelliferone) O,O-diethyl thiophosphate, and O-(3-chloro-4-methylumbelliferone) O,O-dimethyl thiophosphate. 1,2-methylenedioxy-4-[2-(octylsulfinyl)propyl]benzene was included as a standard of comparison. The toxicants were tested at concentrations of 0.005, 0.0025, and 0.001 percent, alone and in combination with each synergist at a ratio of 1:10. The results of the tests are presented in Table 2. As can be seen, all the synergists increased the toxicity of the phosphates.

Further tests were conducted with a concentration of 0.005 percent of the phosphate and 0.05 percent of each synergist to determine the residual effectiveness of the materials. Results of these tests are presented in Table 3. All 17 synergists increased or prolonged the residual action of umbelliferone esters of thiophosphoric acid to a remarkable degree.

Table 2.—Effectiveness of certain umbelliferone esters of thiophosphoric acid at different concentrations in combination with various synergists. (Ratio of synergist to toxicant 10:1; 20 adult lice (10 of each sex) exposed for 24 hours.)

¹ Names of compounds are given in Table 2.

Six other phosphates were selected for tests similar to those above, using 1,2-methylenedioxy-4-[2-octylsulfinyl]propylbenzene as the synergist. The phosphates were tetraethyl dithiopyrophosphate, tetrapropyl dithiopyrophosphate, O,O-diethyl O-(2-ethylmercapto)ethyl thiophosphate, O,O-dimethyl dithiophosphate of diethyl mercaptosuccinate, O-(2-chloro-4-nitrophenyl) O,O-dimethyl thiophosphate, and the O-ethyl O-p-nitrophenyl benzenethiophosphonate. The minimum effective concentration of these materials, alone and in combination with the synergist, are shown in Table 4.

The residual effectiveness of the various synergistic materials with the phosphoric acid esters when applied to cloth has been clearly demonstrated. When applied as powders, these materials also have a remarkable residual effectiveness, as shown in Table 5.

Table 4.—Results of beaker tests with selected phosphate compounds at low concentrations alone and combined with a synergist, 1,2-methylenedioxy-4-[2-(octylsulfinyl)propyl]benzene. (Ratio of toxicant to synergist 1:10; 20 adult lice (10 of each sex) exposed for 24 hours.)

We claim:

1. An insecticide comprising a mixture containing as a toxicant an organic phosphate having the formula

wherein R_1 and R_2 are identical alkyl radicals selected from the group consisting of methyl and ethyl, and R_3 is a member of the group consisting of hydrogen and chlorine and, as a synergist therefor, a member selected from the group consisting of 1,2-methylenedioxy-4-[2-(octylsulfinyl)propyl] benzene and the alpha-isopropylpiperonyl ester of chrysanthemum monocarboxylic acid, said toxicant and synergist being present in the proportions of about from .0025% to .005% of toxicant to .025% to .05%, respectively, of the synergist.

2. The insecticide of claim 1 wherein the synergist is 1,2-methylenedioxy-4-[2-(octylsulfinyl)propyl] benzene.

3. The insecticide in claim 1 wherein the toxicant is O,O-diethyl O-4-methylumbelliferone thiophosphate and the synergist is 1,2-methylenedioxy-4-[2-(octylsulfinyl)propyl] benzene.

4. The insecticide of claim 1 wherein the toxicant is O-(3-chloro-4-methylumbelliferone) O,O-diethyl thiophosphate and the synergist is 1,2-methylenedioxy-4-[2-(octylsulfinyl)propyl] benzene.

5. The insecticide of claim 1 wherein the toxicant is O-(3-chloro-4-methylumbelliferone) O,O-dimethyl thiophosphate and the synergist is 1,2-methylenedioxy-4-[2-(octylsulfinyl)propyl] benzene.

phosphate and the synergist is 1,2-methylenedioxy-4-[2-(octylsulfinyl)propyl] benzene.

6. The insecticide of claim 1 wherein the synergist is the alpha-isopropylpiperonyl ester of chrysanthemum monocarboxylic acid.

7. The insecticide of claim 1 wherein the toxicant is O,O-diethyl O-4-methylumbelliferone thiophosphate and the synergist is the alpha-isopropylpiperonyl ester of chrysanthemum monocarboxylic acid.

10 8. The insecticide of claim 1 wherein the toxicant is O-(3-chloro-4-methylumbelliferone) O,O-diethyl thiophosphate and the synergist is the alpha-isopropylpiperonyl ester of chrysanthemum monocarboxylic acid.

9. The insecticide of claim 1 wherein the toxicant is 15 O-(3-chloro-4-methylumbelliferone) O,O-dimethyl thiophosphate and the synergist is the alpha-isopropylpiperonyl ester of chrysanthemum monocarboxylic acid.
